[57] **CLAIM**

The ornamental design for a shoe sole, as shown and described.

DESCRIPTION

FIG. 1 is a cross sectional view taken on line 1—1 of FIG. 2 of a shoe sole showing my new design, the broken lines showing a boot throughout the views being for illustrative purposes only and forming no part of the claimed design; FIG. 2 is a bottom plan view of a shoe sole showing my new design;

FIG. 3 is a top plan view of FIG. 2;

FIG. 4 is a left side elevational view of FIG. 2;

FIG. 5 is a rear elevational view of FIG. 2; and,

FIG. 6 is a front elevational view of FIG. 2.
